[57] CLAIM

The ornamental design for lighted house number signage, as shown and described.

DESCRIPTION

FIG. 1 is a front view of lighted house number signage, showing my new design;

FIG. 2 is a top plan view;

FIG. 3 is a left elevational view, the right elevational view being a mirror image thereof;

FIG. 4 is a rear elevational view;

FIG. 5 is a bottom plan view; and,

FIG. 6 is a perspective view.

The broken lines are shown for illustrative purposes only and form no part of the claimed design.
